CLAIM

The ornamental design for a nozzle cap for ink bottle for
printer, as shown and described.

DESCRIPTION

FIG. 1 is a front view of the nozzle cap for ink bottle for
printer, shown without the ink bottle;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a left side perspective view thereof;

FIG. 8 is a right side perspective view thereof; and,

FIG. 9 is a bottom perspective view thereof.

1 Claim, 9 Drawing Sheets
